UNITED STATES PATENT OFFICE.

HENRY L. FERRIS, OF HARVARD, ILLINOIS, ASSIGNOR TO HUNT, HELM & FERRIS, OF SAME PLACE.

WINDMILL-REGULATOR.

SPECIFICATION forming part of Letters Patent No. 417,416, dated December 17, 1889.

Application filed July 26, 1889. Serial No. 318,777. (No model.)

To all whom it may concern:

Be it known that I, HENRY L. FERRIS, of Harvard, in the county of McHenry and State of Illinois, have invented certain new and useful Improvements in Windmill-Regulators; and I do hereby declare that the following is a full, clear, and exact description thereof, reference being had to the accompanying drawings, and to the letters of reference 10 marked thereon, which form a part of this specification.

This invention relates to devices for regulating windmills whereby the operating-wheel may be thrown "out of the wind," and the 15 pumping of water thereby stopped, and also to throw the operating-wheel back "into the wind" automatically as the water is lowered in the tank, and thus causing the pumping of water to be resumed.

20 The invention consists in the novel construction and combination hereinafter more fully described and claimed.

In the drawings, Figure 1 is a side view of a portion of the upper structure or frame for 25 the support of a windmill, having my novel regulating device attached thereto and shown in end elevation. Fig. 2 is a side elevation of the device, the parts being shown in a changed position from that shown in Fig. 1.

30 Fig. 3 is a side elevation of the same, the parts being in the same positions shown in Fig. 1. Fig. 4 is a plan view of the device in position illustrated in Fig. 3. Figs. 5 and 6 are side views of the ratchet-wheel and the gripping devices, showing the latter in different 35 positions. Figs. 7 and 8 are enlarged views of the clutch and the flange on the ratchet-wheel engaged thereby.

In said drawings, A A are suitable cross-beams of the tower A' or windmill-support.

A² is an ordinary water-tank secured at 40 convenient distance from said beams A A upon the cross-beams A³ A³, or by other suitable means, and provided at or near its top 45 with a water-supply pipe a, leading from a pump. (Not shown in the drawings.)

A⁴ is a float within the tank A², and said float A⁴ is connected, by the rod, wire, or cable a', the bell-crank lever a², and a rod, wire, 50 or cable a³, with a lever upon my regulating

device, as will be hereinafter more fully stated.

B is a vertically-reciprocating pump-rod, connected in the usual manner at its upper end to the crank-shaft of the windmill and 55 at its lower end to a pump.

Neither the windmill, the pump, nor the connections of the rod B form any part of the present invention. These parts have not been illustrated, as my invention is not to be 60 confined to any particular windmill.

Upon and between the said cross-beams A is a flat metal plate B', constituting a frame for the immediate support of the regulating device. The use of this frame-plate, while 65 preferred, is, however, not essential to the operation of the regulating device, as the latter may obviously be supported directly upon the cross-beams A A. Upon said plate (or secured to the beams A A) are the two journal-bearings B², which support a shaft b.

C is a ratchet-wheel mounted loosely upon the shaft b, and having an annular flange c located near the periphery of the wheel for engagement with suitable friction devices. 75

C' is a lever loosely mounted at one end over the shaft b, and having a slot c' in its other working end. A bolt c² and nut c³ secures this lever C' to the pump-rod B.

C² is a pawl pivotally secured to the lever 80 C' in position to engage the teeth c' of the ratchet-wheel C. A weighted arm C⁴ extends from this pawl to one side of the wheel C, and tends to constantly keep said pawl in engagement with the teeth c'. 85

Pivoted to a lug b', depending from the central portion of the frame-plate B', is a gravity-pawl B³, adapted also to engage the ratchet-wheel teeth, to prevent thereby the movement of the said wheel toward the pawl 90 B³, while permitting it to be freely rotated in the opposite direction. This pawl B³ may be pivoted to one of the cross-beams A, if desired, as will be readily understood.

Each upward stroke of the pump-rod B 95 carries the moving end of the lever C' upward. The pawl C² engages one of the teeth c', and as the upward movement of the arm-lever C' continues the ratchet-wheel is rotated upon its shaft b. When the rod B de- 100

seends, it carries the lever C' downward, the pawl C^2 slipping over the teeth c^4 , while the pawl B^3 engages one of said teeth and prevents a return of the ratchet-wheel. Loosely mounted upon the shaft b on the end adjacent to the flange c is a spool or sleeve D , which carries a lug or arm d .

D' is a two-armed lever, pivoted at d' to the lug d , and having the end of its lower arm bifurcated, so that said arm may encircle the said shaft b .

D^2 is a spring placed around the shaft b and interposed between the end of the loose sleeve D and the bifurcated arm of the lever D' . One end of the sleeve rests against the face of the ratchet-wheel C , as will be readily understood, and therefore the spring D^2 tends constantly to press the bifurcated arm of the lever D' outwardly or away from the said sleeve. The tendency is checked, except as hereinbelow stated, by the pull of the float A^4 , which, when the water in the tank is exhausted, acts as a weight.

E is a lever pivoted at e to a suitable lug 25 on the frame-plate B' , (or on the cross-bar A ,) and connected at its lower end with the cable or rod a^3 . The upper end or arm e' is bifurcated to surround the shaft b , and presses against the bifurcated arm of the lever D' . The weight of the float A^4 thus tends to hold the lever D' in the position illustrated in Fig. 1, while the spring D exerts its power in the opposite direction.

D^3 is a bracket-arm extending out from the sleeve D , it being integral therewith and with the arm d . The gripping-lever arm F is pivoted at f to the end of the bracket-arm D^3 . The outer upturned end f' of this arm F is attached to the cable, wire, or rod F' , by pulling on which the windmill is turned out of the wind, while the other and shorter arm f^2 is bent upwardly, so that its bifurcated end f^3 will engage the rounded end of (or a pin or stud on) the arm D' . This lever F is provided with two raised lugs or projections f^4 f^4 , which constitute the clutch mechanism. The adjacent faces of these lugs f^4 f^4 are substantially parallel, and are at such distance apart only as will admit the free passage between them of the flange c of the ratchet-wheel when the arm F is in its normal position, as shown in Figs. 1, 3, 4, 5, and 7. When said lever is moved very slightly from the normal position, the position of the faces of the lugs f^4 f^4 is changed, so that they bear against the rim or flange c of the ratchet-wheel, one on the inside and one on the outside, as shown. The greater the movement the greater the frictional bearing of these parts. Such movement is communicated to the lever F by the spring D^2 .

G is a cable, wire, or rod engaging at one end the lower end of the lever E , whereby by pulling on said cable G the lever E may be moved by hand against the pressure of the spring D^2 .

The operation of my device is as follows:

The parts being in the position illustrated in Figs. 1, 3, 4, 5, and 7, the windmill in the wind, and the pump-rod B moving up and down, and thereby, through the lever C' , rotating the ratchet-wheel, except when the pawl C^2 is disengaged from the teeth of the ratchet-wheel, when a sufficient quantity of water has been pumped into the tank A^2 , the float A^4 will have raised to such a position as to cause a slackening of the cable a' , whereupon, the pressure against the spring D^2 , through the lever a^3 , cable a^3 , and lever E , being removed, the spring forces the bifurcated lower end of the arm D' outwardly, and at the same time, through the other end arm of this lever D' , draws the end f^3 of the arm F downwardly. The lugs f^4 f^4 now firmly engage the rim or flange c , thus uniting the arm F to the ratchet-wheel C . As the ratchet-wheel is revolved by the continued reciprocating movement of pump-rod and the lever C' , the wheel carries with it the lever F , until finally said lever is in the position shown in Figs. 2, 6, and 8. When the water is being drawn out of the tank, the weighted float A^4 descends, and thereby automatically throws the governing-wheel into the wind again by exerting pressure against the spring D^2 , thereby throwing the arm f^2 up and loosening the grip of the clutches f^4 f^4 on the flange c . As will be readily understood, the cable F' being thereby slackened, the operating-wheel promptly flies into the wind and at once begins work. It will thus readily be understood that my improved device regulates the action of the wind-wheel both when in the wind and when out of the wind. Should it be desired, however, to throw the mill into the wind for a few moments at a time—as, for example, long enough to pump a pail full of water—this may be accomplished by a downward pull upon the cable G . This cable G is trained over the pulley g , and is connected to the lower end of the lever E . The downward pull upon the cable G causes the upper arm of the lever E to press the lower end of the lever D' toward and against the spring D^2 , raise the upper arm of the lever D' and the short arm of the gripping-lever F , and thereby loosen the grip of the lugs f^4 f^4 on the flange c . The friction being thus released, the windmill swings into the wind, pulling the lever F up into its normal position. Upon releasing the tension on the cable G the spring D^2 operates the levers D' and F again, as heretofore explained, and the lugs f^4 f^4 again grip the flange c of the ratchet-wheel.

It is found that even when the mill is out of the wind the direction of the wind will suddenly change sufficiently to operate the mill for a short time. In such cases provision must be made to prevent the continued rotation of the ratchet-wheel and the parts connected to it, lest these parts become strained, twisted, or broken. To obviate such trouble, I place an arm H upon the sleeve D in such

position that when the arm F has reached the position illustrated in Fig. 2 the end h of said arm will have engaged the under side of the pawl C² and will have raised said pawl 5 out of engagement with the ratchet-wheel. It will be manifest that in this position any oscillation of the arm C' will not cause any rotation of the ratchet-wheel.

What I claim, and desire to secure by Letters Patent, is as follows:

1. In combination with the pump-rod of a windmill and a cable for drawing the mill out of the wind, a ratchet-wheel, a lever connected to the pump-rod and having a pawl to engage the ratchet-wheel, a clutch-lever connected to the windmill-cable and having clutches for engagement with the rim of said ratchet-wheel, and mechanism, substantially as described, for causing said clutch-lever to frictionally engage the ratchet-wheel, substantially as described.

2. The combination, with a pump-rod and a cable for drawing the mill out of the wind, of a clutch-lever connected to said cable, a ratchet-wheel provided with a flange, a lever connected to the pump-rod and having a pawl thereon for engagement with the ratchet-wheel, a pivoted lever, one arm of which engages the said clutch-lever, and a spring in engagement with the other end of said pivoted lever, whereby by the pressure of said spring the clutch-lever is caused to frictionally engage the flange of the ratchet-wheel, substantially as described.

3. The combination, with a pump-rod of a windmill and a cable for drawing the mill out of the wind, of a water-tank and a weighted float therein connected to said cable, a pawl and ratchet-wheel connected to said pump-rod, and a clutch-lever connected to said cable and adapted to grip the said ratchet-wheel when the weight of the float is relieved by the raising of the water in the tank, substantially as described.

4. The combination, with a pump-rod of a windmill and a cable for throwing the mill

out of the wind, of a clutch-lever connected to said cable, a pawl-and-ratchet mechanism, substantially as described, operated by the pump-rod, a spring on the ratchet-wheel 50 shaft normally tending to engage the clutch-lever with the ratchet-wheel, a pivoted lever, one end of which engages said spring, and a weight suspended from the other end of said pivotal lever, whereby said clutch-lever is 55 normally held free from engagement with said ratchet-wheel, substantially as described.

5. An apparatus for automatically throwing a windmill out of the wind, consisting of a lever connected to the windmill, a pawl-and-ratchet mechanism, substantially as described, operated by the pump-rod, a spring for uniting the said lever to the said ratchet, a weighted float adapted to release the spring, and an arm connected with said lever and 65 adapted to disengage said pawl from said ratchet when the mill has been thrown out of the wind, substantially as and for the purpose specified.

6. An apparatus for automatically throwing a windmill out of the wind, consisting of an operating-cable connected to a clutch-lever, a pawl and ratchet, said pawl being operated by the pump-rod and said ratchet having a flange for engagement with the clutch-lever, 75 a spring for operating said clutch-lever, a pivoted lever and a weight suspended therefrom, whereby the clutch-lever is held out of engagement with the said ratchet, said weight being a float adapted to rise in a tank of 80 water and release said pivoted lever, and a movable arm for disengaging the said pawl from the ratchet when the windmill is out of the wind, substantially as specified.

In testimony that I claim the foregoing as 85 my invention I affix my signature in presence of two witnesses.

HENRY L. FERRIS.
